UNITED STATES PATENT OFFICE.

LUTHER G. BILLINGS, OF WASHINGTON, DISTRICT OF COLUMBIA.

DESIGN FOR A CABINET FOR TYPE-WRITERS, &c.

SPECIFICATION forming part of Design No. 19,410, dated November 12, 1889.

Application filed March 22, 1888. Serial No. 268,184. Term of patent 3½ years.

To all whom it may concern:

Be it known that I, LUTHER G. BILLINGS, a citizen of the United States, residing at Washington, in the District of Columbia, have invented a certain new and original Design for Cabinets for Type-Writers and other Machines, of which the following is a full, clear, and exact description.

My invention consists in a design for cabinets for type-writers and other machines, the leading features of which are raised panels for the sides, door, and drawers, a flat rolling top for the well or recess which is ordinarily used to receive and conceal the type-writer, a molded and fretted fender for the top, and certain moldings in the corner-posts and stiles of the door and panels, all as will be understood more fully from the description and claim following.

In the accompanying drawings, illustrating my design, Figure 1 is a perspective view; and Fig. 2, a vertical section taken through the right-hand side of the cabinet in Fig. 1, so as to show more in detail the raised panels and moldings.

The cabinet comprises the flat top *a*, having a rolling section *b* over the well or recess *c*, the longitudinal fender *d*, and the two sides *e* and *f*, the side *e* containing the door *g*, drawer *h*, and shelf *i*, and the side *f* containing the tier of drawers *j* and shelf *k*. Stated thus generally, the cabinet is of ordinary construction, with the exception, however, of the flat roll-top.

The ends or sides of the cabinet are produced with raised panels *l*, with their stiles having a sort of compound filleted, beaded, and canting molding. The same sort of molding runs lengthwise of the fender *d*, and said fender has stellar frets *m* between these moldings, and the corner-posts *n n* of the fender are in outline a sort of cavetto bead and fillet molding, with their upper edges having sunken beads. The drawers have raised panels on their fronts and suitable handles or pulls. The door has a raised panel, and its stiles are molded, as are the stiles of the side panels. The shelves *i* and *k* have beaded fronts. The stiles of the walls of the well or recess *c* are also molded like the other stiles. The top overhangs the parts *e* and *f*, and the angle is filled with a molding *o*, which may be described as a quirk-ogee bead and fillet. The molding *p* extends around the entire front of the base of the cabinet, and may be described as a cavetto bead and fillet molding.

Some parts shown but not described are not essential to this design.

What I claim is—
The design for cabinets for type-writers and other machines, substantially as shown.
In testimony whereof I have hereunto set my hand this 12th day of March, A. D. 1888.

LUTHER G. BILLINGS.
